UNITED STATES PATENT OFFICE

HARRY W. BREWER, OF ST. LOUIS, MISSOURI

PROCESS AND APPARATUS FOR COLOR-STRIPING PENCILS AND THE LIKE

Application filed June 28, 1930. Serial No. 464,668.

This invention relates generally to the color-finishing of pencils and the like and, more particularly, to a certain new and useful process and apparatus for color-striping pencils and the like in the finishing thereof.

My invention has for its chief objects to provide a pencil, pen-holder, or the like finished in two or more colors arranged in a plurality of longitudinal stripes or panels on the pencil or other such body in a highly attractive and artistic manner and appearance; to provide a process or method for color-striping a pencil-body or the like in a simple, expeditious, and highly economical and efficient manner; and to provide a new and novel apparatus for carrying out and practicing such process or method especially adapted for the continuous or so-called "mass production" of pencils and the like color-finished in accordance with my invention.

And with the above and other objects in view, my invention resides in the novel features of form, construction, arrangement, and combination of parts and in the method of use thereof, all as hereinafter described and pointed out in the claims.

In the accompanying drawings (two sheets),—

Figure 1 is a diagrammatic arrangement of apparatus adapted for employment in practicing my new method of pencil color-finishing;

Figure 2 is an enlarged fragmentary sectional view of such apparatus, taken approximately along the line 2—2, Figure 1;

Figure 3 is a sectional view of the first coat wiper, the view being taken along the line 3—3, Figure 2;

Figure 4 is a sectional view of the preferred form of second-coat wiper, the view being taken along the line 4—4, Figure 2;

Figure 5 is a view of a prismatic pencil color-finished according to my invention with the second-coat wiper shown in Figures 2 and 3;

Figure 6 is a sectional view similar to Figure 4, showing a modified form of second-coat wiper;

Figure 7 is a view in elevation of a pris-

matic pencil color-finished according to my invention with the second-coat-wiper shown in Figure 6;

Figure 8 is a sectional view similar to Figure 4, showing another modified form of second-coat wiper; and

Figure 9 is a view in elevation of a cylindrical pencil color-finished according to my invention with a modified form of first-coat wiper and the second-coat wiper shown in Figure 8.

My invention may be employed for color-finishing round, hexagonal, octagonal, flat, and oval pencils and the like, and my new process of color-finishing consists, generally, in successively coating a pencil-body or the like with preferably dissimilar colors and removing portions of the overlaid or second coat for exposing both colors on the pencil. And for carrying out the process, I provide an apparatus adapted to be worked in stages, which includes a pencil feeder A, a color-applying means or paint-pot B co-operating with a so-called first-coat wiper C, complementary to the particular pencil-body, a suitable drying device D, a second pencil-feeder E, a second color-applying means or paint-pot F co-operating with a so-called second-coat wiper G complementary only in part to the particular pencil-body, and, preferably, a suitable conveyer H for transporting the finished work, all as best seen in Figure 1.

If more than two paint-coats are to be applied to the particular pencil, additional successive drying, color-applying, and wiping stages may be provided, as may be required suitably for the purposes intended.

Referring now more in detail and by reference characters to the drawings, in Figures 1 to 4, inclusive, I illustrate one or the preferred form of my invention, especially, though not exclusively, adapted for color-finishing an hexagonal-bodied or like prismatic pencil K.

For such purpose, the paint-pot B preferably includes a suitable paint-container 1, having in two of its opposing walls registering apertures 2, 3, the aperture 2 being provided with a suitable pencil-receptive packing 4.

Disposed in co-operation and registration with the opposite aperture 3, is the first-coat wiper C, which comprises a suitably formed body member 5 constructed of a rubber or body member 5 of the wiper C tapers from its outer smaller end in a frusto-conical shape and at its inner end has a flange 6 adapted to be engaged by an annular suitably apertured retaining member 7 suitably secured to the pot B for suitably mounting the wiper C thereupon. The wiper C has a pencil-receptive preferably prismatic passage or bore 8, whose yieldable walls are substantially complementary to, and adapted for engagement by, the pencil K, as best seen in Figure 3.

In carrying out this stage of the process, I prefer to arrange the feeder A for pushing the pencils K in endwise abutting relation successively through the pot B and the wiper C. In the pot B I provide a body of suitable liquid paint, enamel, or like surface covering material, in tint *a* of the color selected for the first or under-coat of the pencil K. The thick coat of the paint *a*, adhering to the surface of the unmersed pencil K while passing through the pot B, is suitably smoothed on the pencil by the walls of the passage 8 of the wiper C, which, as most clearly seen in Figure 3, resiliently embrace or grip the entire peripheral surface of the pencil, in such manner as to remove and return to the pot B any surplus paint *a* and leave a thin film or coating of the paint *a* uniformly over the surface of the now painted or first colored pencil K'.

I prefer to arrange the apparatus so that the painted or colored pencils K' discharge from the wiper C onto a suitable conveyer or drying device D, the latter being shown, in the present instance, as a drying wheel or revolving carrier on which the pencils K' remain until the paint *a* has dried, whereupon the now dried pencils K' are disposed by the device D in suitable position for delivery, manually or otherwise, to the feeding device E, which feeds successive pencils K', preferably in endwise abutting relation, to and through the paint-pot F, which is substantially like the pot B, that is, includes a receptacle 1', spaced registering apertures 2', 3', and packing 4'. In like manner, the second coat wiper G is mounted by a retainer 7' on the pot F, the wiper G also including a body portion 5' and flange 6', substantially similar to, and interchangeable on the pots B, F, with the wiper C, for a purpose later appearing. The wiper G, thus disposed on the pot F suitably to yieldingly receive and resiliently grip the successive pencils K' fed therethrough, is constructed of rubber or like yieldable or elastic material, like the wiper C, but differs therefrom in having its pencil-

receptive passage or bore 9 of a cylindrical cross-section, whose walls yield in their engagement with the corners 10 of the meeting faces 11 of the pencil K' and are hence, in such respect and position, only in part complementary to the pencil-body. 70

In the pot F, I provide a suitable liquid paint *b* of the color selected for the second or overcoating of the pencil, a thick coat of the paint *b* adhering to the immersed undercoating *a* of the pencil K' passing through the pot F. The so coated pencil then longitudinally shiftably engages the normally cylindrical but elastic walls of the passage 9, which are sufficiently distorted by reason of the prismatic shape of the pencil to leave a slight clearance 12, shown greatly exaggerated in Figures 2 and 4, between said walls and the respective faces 11 of the pencil-stock, for removing surplus paint from said faces 11 while leaving a coating or film of paint *a* for providing a good body color to the pencil. 75 80 85

However, at the corners or edges 10 of the pencil body, the elastic walls of the passage 9 are compressed upon the pencil stick in such manner as to scrape and substantially remove all of the coating *b* from, and thereby expose, the under coat *a* at said corners 10 of the pencil, as best seen in Figure 5, the finished pencil being designated at K'', the overcoating being shown at *b*, and the under-coating at *a*. It will be seen that the body color of the pencil K' is formed by the second coating *b* applied in panel-like formation on the respective faces 11 of the pencil, and that such panels are provided with an edging or striping, as may be said, of the color of the first or undercoating exposed at the corners 10 of the pencil, thus producing a two-toned color effect in a highly effective, artistic, and inexpensive manner. 90 95 100 105

I prefer to discharge the pencils K'' on to a suitable conveyer or drying device H, which is shown, in the present instance, as a straight line conveying device, on which the pencils K'' preferably remain until the second coat *b* has dried. 110

In Figure 6 is shown a modified form of second-coat wiper G' also adapted for use with a hexagonal or like peripherally angular pencil L. The wiper G' is substantially in use, construction, and material like the wiper G, and hence in such respects is not more particularly described here. The wiper G', however, differs from the wiper G in the respect that the walls of the pencil-receptive passage or bore 13 of the wiper G' have longitudinal parts 14 adapted to resiliently engage alternate faces 15 of the pencil-body L for scraping or removing therefrom the second-coat of color and hence exposing the first coat *a* thereat, as best seen in Fig- 115 120 125 130

ure 7. Intermediate the parts 14, the walls of the passage 13 are relieved or provided with longitudinal channels 16 so as to cause the walls of the passage 13 to be substantially complementary only in part to the pencil body and hence spaced from the corresponding intervening faces 17 of the pencil-body, which hence retain the second coat of color *b*, also as best seen in Figure 7.

10 I might add that, except for the differences pointed out, the process of color finishing the pencil when employing the wiper *G'* substantially the same as I have heretofore described, when using the wiper *G*.

15 In Figure 8 is shown a further modified form of second-coat wiper *G''*, adapted for use with a cylindrical or like peripherally curved pencil *M*. The wiper *G''* is substantially in use, construction, and material like the wiper *G*, and hence in such respects is also not more particularly described here. The wiper *G''*, however, differs from the wiper *G* in the respect that the walls of the pencil receptive passage or bore 18 of the wiper *G''* are circumferentially interrupted providing longitudinally extending transversely arcuate parts 19, whereby the wiper *G''* is adapted to yieldingly or resiliently engage successive correspondingly circumferential panel-like portions 20 of the pencil-body *M* for scrapingly removing therefrom the second coat of color and hence exposing the first coat *a* thereat, as best seen in Figure 9. Intermediate the parts 19, the walls of the passage 18 are relieved or provided with longitudinal grooves or channels 21, so as to cause the walls of the passage 18 to be substantially complementary only in part to the pencil body and hence spaced from corresponding longitudinally extending arcuate portions 22 intervening the portions 20 of the pencil-body *M*, which hence retain the second coat of color *b*, also as best seen in Figure 9.

25 I might add that the process of color-finishing the pencil when employing the wiper *G''*, is also substantially the same as that when using the wiper *G*, except that, in addition to the differences above pointed out, for the first-stage wiper *C* is substituted a wiper complementary to the pencil-body *M*, which modification of the process may be readily effected, for example, by substituting a wiper *G* for the wiper *C*, as will be readily understood.

30 It will be obvious that wipers having the general characteristics of those shown may be constructed for use with pencils of prismatic contours differing from those illustrated. For example, the second stage wipers *G*, *G'* may be modified for use with flat sided carpenters' pencils and the like, a suitable modification being also made in the first stage wiper *C*. Likewise, the second-stage wiper *G''* may be modified for use with oval or elliptical pencils, the wiper *C* being, of

course, correspondingly modified, and other changes and modifications will, with the aid of this disclosure, readily suggest themselves to those skilled in the art of pencil manufacture.

70 It will be seen that my invention accomplishes its objects, by providing a new and novel process for the production of striped pencils and apparatus therefor, which in simplicity, adaptability, facility and economy of use and employment is of highly efficient and practical utility in the art of pencil color-finishing.

75 I might add that, while I have employed the conventional standards as a matter of convenience in preparing the drawings, and hence shown the color *a* as "blue", and the color *b* as "red", so as to provide for a red body with blue striping, I prefer in practice to employ a dark body or over color *b*, as red, blue, green or the like, and a light ground or under color *a*, as white, yellow, gold, or the like, such as may provide the most agreeable contrasts in the finish of the pencil. It is to be understood that, while for convenience and simplicity of terminology in description, I have employed the term "pencil" or "pencils" in the foregoing specification and appended claims, I desire to be understood, in such regard, as referring generally 80 to the common lead-pencil, to penholders, fountain pens, so-called mechanical pencils, and other like or similar elongated bodies or shells adaptable in form or purpose, for 85 color-finishing, as hereinbefore set forth.

90 It is to be further understood that any suitable contrasting colors or tints may be employed, and that changes and modifications in the details of the process and in the apparatus may be made and substituted for 95 those herein shown and described without departing from the nature and principle of my invention, as defined in the appended claims.

100 Having thus described my invention, what I claim and desire to secure by Letters 110 Patent is:

1. That process of pencil-finishing which consists in projecting a wet-coated pencil-body through the bore of a wiping-member for removing portions only of said wet coating.

115 2. That process of pencil-finishing which consists in endwise projecting a wet-coated pencil-body through the bore of a wiping-member for removing portions only of said wet coating longitudinally of the pencil-body.

120 3. That process of pencil-finishing which consists in providing a pencil-body with a liquid paint-coating of one color, passing the coated pencil-body endwise through the bore of a wiper-member for removing surplus paint from the pencil-body and then drying said coating, providing said coated pencil-body with a liquid paint-coating of another 130

color, and then passing the so freshly coated pencil-body endwise through the bore of a second wiping-member for removing said second coating from portions only of the pencil-body for stripewise longitudinally of the pencil-body exposing said first coating.

4. That process of pencil-finishing which consists in providing a pencil-body with a liquid paint-coating of one color, passing the 10 coated pencil endwise through the bore of a wiping-member for removing surplus paint from the pencil-body and then drying said coating, providing said coated pencil-body with a liquid paint-coating of another color 15 and then passing the so freshly coated pencil-body endwise through a second wiping-member bore complementary only in part to the contour of the pencil-body for removing corresponding parts only of the second coating for exposing both colors on the pencil-body.

5. That process of longitudinally striping a pencil-body having a coating of one color, which consists in overlaying said first coating with a coating of another color, and then 25 projecting the freshly coated pencil-body endwise through a wiping-member bore complementary only in part to the contour of the pencil-body for removing corresponding portions only of said overlaid coating.

6. Means for removing wet-coloring matter from the surface of a pencil-body, said means including a member having a core for accommodating the projection of the pencil- 35 body endwise through said member, the wall of said bore being yieldable and complementary in part only to the contour of the pencil-body for resiliently gripping portions only of the projected pencil-body.

40 7. Means for removing wet-coloring matter from the surface of a pencil-body, said means including a member having a bore for accommodating the projection of the pencil-body endwise through said member, the wall of said bore being yieldable and longitudinally channeled for resiliently gripping portions only of the projected pencil-body.

In testimony whereof, I have signed my name to this specification.

HARRY W. BREWER.
